UNITED STATES PATENT OFFICE.

GEORGE FUSSNER, OF MENOMINEE, MICHIGAN, ASSIGNOR TO SIGNAL ELECTRIC MFG. CO., A CORPORATION OF MICHIGAN.

ELECTROMAGNETIC APPARATUS.

Application filed July 7, 1920. Serial No. 394,487.

To all whom it may concern:

Be it known that I, GEORGE FUSSNER, a citizen of the Republic of Germany, and resident of Menominee, in the county of 5 Menominee and State of Michigan, have invented certain new and useful Improvements in Electromagnetic Apparatus, of which the following is a specification.

My present invention relates to electro- 10 magnetic apparatus and with regard to the more specific features thereof to electromagnetic telegraph relays.

An object of the invention is to provide a construction of the above type which shall 15 be relatively cheap and compact in construction and reliable and efficient in action.

According to one of the features of my invention the standard for carrying the electromagnet coil structure and the support for 20 carrying the stationary relay contact are disposed at opposite ends of said coil structure or cores and are of such simple shape that they can be and preferably are made from brass stampings.

According to another feature of the invention the core or cores of the electromagnet are employed for conducting the current to the contact-carrying support, eliminating the need for separate elements for this pur- 25 pose and dispensing with insulation elements otherwise required.

According to another feature of the invention the electrical contact-carrying support is preferably mounted in contact with 30 the solenoids and upon the projecting end of the core structure and to secure a short air gap the armature is pivoted in proximity to said core ends, the interference resulting from the combined lengths of the cooperat- 35 40 ing contacts on the support and the armature being avoided by forming preferably the armature with a deflection of appropriate extent, away from the support.

A preferred embodiment of the invention 45 is shown in the drawings in which:

Fig. 1 is a plan view of the relay,

Fig. 2 is a side elevation thereof,

Fig. 3 is a transverse sectional view taken on the line 3—3 of Fig. 2,

Fig. 4 is an end elevation viewed from the left end in Fig. 2, and;

Fig. 5 is a longitudinal section through one of the coils of the electromagnet.

Referring now to the drawings there is 55 shown a base 1 preferably of wood mounted

upon a metallic supporting frame 2. A stamped or sheet brass standard 3 has a foot 4 secured to the base by screws as at 5 and an upstanding leg 6 to which the electro- magnet unit 7 is secured. The unit 7 prefer- 60 ably comprises a magnetic cross bar or piece 8 to which are secured preferably by screws as at 9 in parallel relation the magnetic cores 10. The cross-piece 8 is centrally secured to the upstanding leg 6 of the standard prefer- 65 ably by a pair of screws 12. The electro- magnetic coils or solenoids 13 encircle the cores with the insulating disks 14 at one end thereof against the cross-piece 8, fiber sleeves 15 being preferably interposed between the 70 cores and the solenoids to insulate the same from each other. The cores project at their free ends for the usual small distance as at 11 beyond the disks 14' on the solenoids. These projections, however, are preferably 75 utilized as an anchor for the contact-carry- ing support C which is preferably formed from a generally T-shaped sheet brass stamping. By preference the head 17 of the

T-shaped blank is provided with a pair of 80 symmetrically arranged circular openings 18 spaced from each other by the same distance as the cores 10 and the contact-carrying sup- port is forced at said openings over the pro- jecting ends 11 of the cores and against the 85 adjacent end disks 14' of the solenoids. By preference the core ends are knurled as shown at 19 to form a secure frictional con- nection. The contact-carrying support thus, besides its primary function aids to maintain 90 the solenoids against sliding movement along the cores and also prevents shifting of the core ends towards or from each other.

It will be seen that there is a direct metal to metal contact between cores 10 and 95 standard 3 at one end and between said cores and the contact-carrying support C at the other end, for a purpose which will appear fully below.

The shank 20 of the T-shaped contact sup- 100 porting blank extends upwardly away from the base, and has a reversely bent end 21, the bend being rounded so that the upper end of the support is U-shaped. The usual adjustable stationary contact 22 is formed 105 on the end of the usual screw 23, there being a lock nut 24 threaded upon the screw and abutting the side of the support opposite the contact to lock said screw in position 110 corresponding to the adjustment of contact

22. The usual insulating stop member 25 is similarly formed upon the end of a similar screw passing through the reversely bent end 21 and similarly locked in place.

5 The armature is shown at 26 and preferably comprises a unitary steel piece having a body portion extending the width between the two cores. The armature is pivoted to the base by means of a pair of 10 pointed screws 27 extending through metallic standards 28 upon the base and contacting the feet 29 of the armature. At the upper end the armature has an integral central upwardly projecting tongue 16 through 15 which preferably extends a metallic pin 30. The part 30' of pin 30 on the side of the tongue adjacent the contact 22 constitutes the movable contact of the relay and the part 30" of said pin on the side adjacent 20 the stop 25 cooperates with said stop serving to limit the distance by which the retracting coil spring 31 can separate the armature from the core. The coil spring 31 is connected to the armature by means 25 of the usual staple 32 and to the base by means of a rotatable headed pin 33 by which the tension of the spring can be adjusted in the well known manner.

By preference, the core ends project only 30 the usual small distance beyond the ends of the solenoids and the air gap 34 between the core ends and the armature is preferably small thereby producing the desirable and efficient short magnetic circuit of low 35 reluctance. With the contact-carrying support C mounted upon the projecting ends of the cores as described and with the short air gap 34 referred to, the distance between said support and the armature is ordinarily 40 less than the combined lengths of the stationary contact 22 and movable contact 30". To avoid interference between the contacts, I preferably employ the simple expedient 45 of forming a double bend 35 in the free end or tongue of the armature, thus disposing the movable contact laterally away from the body of the armature and from the stationary contact, and producing the required clearance. Thus, I produce a more 50 compact, cheaper and more efficient construction than would be possible, for instance, if the armature were secured to a separate, straight contact-carrying lever pivoted at a distance from the core ends 55 greater than the air gap.

Although I prefer to form the deflection or offset portion in the tongue 16 of the armature, it will be understood that the same could be formed at another part of 60 the armature, or it could be formed in the support C or in both the armature and the support. The parts are preferably so arranged that the contact surface of contact 22 is vertically above the pivot of the armature, so that in operation there will be sub-

stantially a face to face engagement between the adjoining surfaces of contacts 22 and 30".

The terminal posts of the relay unit are arranged in the usual manner, the two posts 70 36 and 37 for the energizing current being connected by conductors not shown to the terminals of the two solenoids 13 which are connected in series as at 38. The terminals of the relay circuit are shown at 39 and 40, 75 the current passing from terminal 39 by way of a conductor not shown to one of the fastening screws 5 for the standard 3 and by way of said standard and the cross bar 8 through the two cores 10 in parallel, thence 80 through the contact-carrying support C to the contact 22 and through the movable contact 30" successively to armature 26, conductor 41 and standard 28, and from the latter through a conductor not shown to the 85 other relay terminal 40.

In my construction the standard 3 and the contact carrying support C are of such simple forms that they can readily be stamped from sheet brass, the cores of the 90 electromagnet performing not only their magnetic function but acting as low resistance electrical conductors for passing the current from the standard to the contact-carrying support. Where the cores are not 95 utilized for carrying the relay current but an integral brass portion connects the standard part 3 at one end of the solenoids, to the contact carrying support 17 at the opposite end, such integral construction of 100 standard, contact support and connecting element is so complex in shape that in general it would have to be cast and then finished at an expense considerably greater than that involved in the construction 105 shown, apart from the consideration that such construction would require a materially greater quantity of metal.

It will be understood that certain of the features of my invention are applicable to 110 a broad range of electromagnetic apparatus other than the telegraph relays to which the invention has its preferred application. The feature, for instance, of mounting the contact-carrying support upon the projecting 115 end of the core or cores and preserving the efficiency of the magnetic circuit without other complications by the simple expedient shown of providing a bend in the armature is of broad application to electromagnetic 120 apparatus generally.

By utilizing the usual projecting ends of the cores to carry the contact-carrying support, I simplify and cheapen the construction as compared with arrangements in 125 which said support is not secured to the electromagnet. By mounting the solenoid construction upon a supporting standard at the end opposite the armature and mounting the contact-carrying support upon the 130

solenoid to extend upwardly therefrom, there is ample space left upon the base adjacent the core end to render possible the pivoting of the armature in close proximity 5 to the core ends for producing the short air gap and the consequent efficient magnetic circuit which could be secured only with difficulty if at all, if the supporting standard and the contact-carrying support were both at the 10 same side of the electromagnetic unit as the armature.

It will be seen that the contact carrying support extends in the space between the coil means and the armature without adding to 15 the reluctance of the magnetic circuit.

It will thus be seen that there is herein described apparatus in which the several features of this invention are embodied, and which apparatus in its action attains the 20 various objects of the invention and is well suited to meet the requirements of practical use.

As many changes could be made in the above construction and many apparently 25 widely different embodiments of this invention could be made without departing from the scope thereof, it is intended that all matter contained in the above description or shown in the accompanying drawings shall 30 be interpreted as illustrative and not in a limiting sense.

I claim:—

1. In electromagnetic apparatus of the type comprising a base, a standard secured 35 thereon, electromagnetic coil means supported at one end by said standard, extending parallel to said base and having core means projecting beyond the opposite end thereof, and an armature pivoted to said 40 base and extending adjacent said latter end and at right angles to the axis of said coil means and carrying a contact; the combination therewith of a nonmagnetic element supported by the end of said coil means and 45 carrying a contact complementary to that on said armature, said element extending in the space between said coil means and said armature without adding to the reluctance of the magnetic circuit.

50 2. The combination in a relay, of a base, a standard secured thereon, electromagnetic coil means supported at one end by said standard and extending parallel to said base, an armature pivotally mounted upon said 55 base and extending substantially at right angles thereto and adjacent the opposite end of said coil means, a contact-carrying support carried by the end of said coil means and interposed therebetween and said armature 60 and extending at right angles to said base, and a contact on said armature adapted to engage the contact on said support.

3. The combination in a relay of a base, a standard secured thereon, an electromagnet 65 comprising a pair of cores parallel to

said base mounted upon said standard and projecting to one side thereof, solenoids surrounding said cores, a contact-carrying support secured to the ends of said cores remote from said standard, and an armature 70 pivoted to said base and having a contact portion cooperating with the contact on said support.

4. The combination in a relay of a base, a standard secured thereon, an electromagnet 75 comprising a pair of cores parallel to and equidistant from said base, mounted upon said standard and projecting to one side thereof, solenoids surrounding said cores, a non-magnetic contact carrying support secured to said projecting ends of the cores and extending away from said base, and an armature pivoted to said base and having a contact portion cooperating with the contact on said support. 80

5. The combination in a relay of a base, a sheet metal standard secured thereon, an electromagnet comprising a pair of cores, a cross bar connecting said cores and constituting part of the magnetic circuit of the 90 electromagnet, means securing said cross bar to said standard, a pair of solenoids surrounding said cores and adjacent said cross bar at one end, the ends of said cores opposite said cross bar projecting from the ends of said solenoids, a sheet metal contact-carrying support having a transverse portion secured to said core ends, said contact-carrying support extending upwardly from said cores, and an armature pivoted to said base 95 and having a contact portion cooperating with the contact on said support.

6. The combination in a relay, of a base, an electromagnet comprising a pair of cores, a magnetic cross piece connecting said cores and secured thereto, and a pair of solenoids surrounding said cores with one end adjacent said cross-piece, a sheet metal standard supporting said electromagnet upon said 100 base, said standard comprising a vertical portion secured to said cross-piece, and a horizontal portion extending from said vertical portion in a direction opposite to that of said cores and secured to said base, said cores projecting beyond the ends of said solenoids 105

remote from said standard, a sheet metal contact-carrying support provided with openings embracing the projecting ends of the cores with a friction fit, said support extending upwardly from said cores and having its free end extending downwardly, an armature pivoted to said base adjacent said 110 projecting core ends and having an integral tongue at its upper end extending between the upwardly and downwardly extending support portions, and a contact upon said tongue aligned to cooperate with the contact upon said support. 115

7. The combination in a relay of a base, a non-magnetic metallic standard secured 120

- thereto, a magnetic core secured to said standard in electrical contact therewith, a solenoid surrounding said core, carried thereby and electrically insulated therefrom, a 5 non-magnetic metallic contact-carrying support carried by the end of said core, and an armature pivoted to said base adjacent said core end and having a contact adapted to cooperate with the contact on said support.
10. 8. The combination in a relay, of a base, a non-magnetic stamped metal standard mounted upon said base, an electromagnet comprising a magnetic cross-piece, a pair of parallel magnetic cores secured thereto, and 15 a pair of solenoids encircling said core, carried thereby and insulated therefrom, metallic means securing said cross-piece to said standard with said cores parallel to said base and equidistant therefrom, a sheet metal 20 non-magnetic contact-carrying support forced over the projecting ends of said cores and electrically connected therewith, and an armature pivoted to said base and having a contact cooperating with the contact on said 25 support.
9. In electromagnetic apparatus, in combination a solenoid, a core extending therethrough and projecting beyond an end thereof, a non-magnetic contact-carrying support 30 having an opening therein through which the projecting core end extends for carrying said support, an armature adjacent and substantially parallel to said core end and carrying a contact for cooperation with the contact on said support, one of said support and armature having an offset portion at the contact-carrying portion to prevent interference between said contacts.
10. The combination in a relay, of an electromagnet including a core and a solenoid surrounding the same, said core projecting beyond an end of said solenoid, a contact-carrying support having an opening fitting over said projecting core end, said support 40 extending at right angles to said core, an armature pivoted adjacent said core, said armature carrying near its free end a contact adapted to coact with the contact on said support, the combined lengths of the 45 contacts between the support and the armature being greater than the distance of said armature from said support, one of said support and armature being deflected away from the other at the region adjacent the 50 contacts to avoid interference between said contacts.
11. The combination of claim 9 in which the contacting surface of said support contact is substantially in the plane in which 55 said armature is pivoted.
12. The combination in a relay, of a base, a standard mounted thereon, an electromagnet comprising a core secured to said standard, and parallel to said base, a solenoid surrounding said core, said core projecting be- 60 yond an end of said solenoid, a contact-carrying support having an opening fitted over said projecting core end and secured thereto, said support extending upwardly from said core, an armature pivoted to said base adjacent said core end and carrying at its free end a contact adapted to coact with the contact on said support, said armature having a double bend adjacent said free end to dispose said contact laterally of the main portion of 65 said armature, and to the side thereof away from the contact on the support.
13. In electromagnetic apparatus, in combination, a core, a solenoid surrounding the same, said core projecting beyond said solenoid at one end, a sheet metal contact-carrying support having an opening fitted over said projecting end and secured thereto, said support extending at right angles to said core and having a reversely extending U-shaped end, an armature pivoted adjacent said support, said support having a contact element upon the leg of the U-shaped end adjacent the core, and an insulating stop portion upon the other leg, the free end of 70 said armature extending between said legs and carrying a contact for cooperation with the contact on said support, said armature having a double bend to dispose the contact-carrying portion substantially parallel to the 75 main portion thereof away from said contact-carrying leg and toward said stop carrying leg thereof.
14. The combination of claim 7 in which the armature is pivoted to the base adjacent 80 said contact-carrying support, in which the combined lengths of the contacts between the support and the armature is greater than the distance between said elements, and in which the free end of the armature is of 85 greatly reduced width and bent away from said support.
15. The combination in a relay of a base, an electromagnet comprising a pair of cores and a pair of solenoids surrounding said 90 cores, said cores projecting beyond the ends of said solenoids, and a contact carrying support provided with openings embracing the projecting ends of the cores with a friction fit, whereby said cores serve to rigidly mount 95 said support, and whereby said support serves to maintain the adjacent ends of the cores against displacement relative to each other.
16. The combination in a relay, of a base, an electromagnet comprising a pair of cores, a magnetic cross-piece connecting said cores and secured thereto, and a pair of solenoids surrounding said cores with one end adjacent 100 said cross-piece, a sheet metal standard supporting said electromagnet on said base, said standard comprising a vertical portion secured to said cross-piece, and a horizontal portion extending from said vertical portion in a direction opposite to that of said 105
17. The combination in a relay, of a base, an electromagnet comprising a pair of cores, a magnetic cross-piece connecting said cores and secured thereto, and a pair of solenoids surrounding said cores with one end adjacent 110 said cross-piece, a sheet metal standard supporting said electromagnet on said base, said standard comprising a vertical portion secured to said cross-piece, and a horizontal portion extending from said vertical portion in a direction opposite to that of said 115
18. The combination in a relay, of a base, an electromagnet comprising a pair of cores, a magnetic cross-piece connecting said cores and secured thereto, and a pair of solenoids surrounding said cores with one end adjacent 120 said cross-piece, a sheet metal standard supporting said electromagnet on said base, said standard comprising a vertical portion secured to said cross-piece, and a horizontal portion extending from said vertical portion in a direction opposite to that of said 125
19. The combination in a relay, of a base, an electromagnet comprising a pair of cores, a magnetic cross-piece connecting said cores and secured thereto, and a pair of solenoids surrounding said cores with one end adjacent 130 said cross-piece, a sheet metal standard supporting said electromagnet on said base, said standard comprising a vertical portion secured to said cross-piece, and a horizontal portion extending from said vertical portion in a direction opposite to that of said

cores and secured to said base, said cores projecting beyond the ends of said solenoids remote from said standard, an armature pivoted to said base adjacent said projecting 5 core ends, a contact carrying support provided with openings embracing the projecting ends of the core with a friction fit, said support extending upwardly from said

cores and having parts carried thereby extending on opposite sides of said armature to 10 limit the movement thereof.

Signed at Menominee in the county of Menominee and State of Michigan this third day of July A. D. 1920.

GEORGE FUSSNER.
